UNITED STATES PATENT OFFICE.

THOMAS WESLEY HOOK, OF SAN ANTONIO, TEXAS.

UNION-GARMENT.

1,368,800.

Specification of Letters Patent. Patented Feb. 15, 1921.

Application filed August 6, 1920. Serial No. 401,622.

To all whom it may concern:

Be it known that I, THOMAS WESLEY HOOK, a citizen of the United States, residing at San Antonio, in the county of Bexar 5 and State of Texas, have invented certain new and useful Improvements in Union-Garments, of which the following is a specification.

This invention relates to union suits or 10 garments of the class in which a section or strip of elastic or semi-elastic woven or knitted material is embodied in the garment at the back of the waist in order to allow the garment to stretch to some extent 15 when the body of the wearer is bent and to afterward return to its normal position. The ribbed cloth ordinarily used for this purpose is efficient for only a short time. It soon becomes permanently stretched 20 or distorted and therefore the size of the garment is unduly increased and a neat fit is lost. Furthermore, experience has demonstrated that the ribbed cloth often tears easily and is unfit for use long before 25 other parts of the garment are unserviceable.

According to my invention I provide 30 means for preventing undue stretching of the ribbed waist section and for assisting it to return to normal condition. For this purpose I use a plurality of short lengths 35 of elastic webbing in the form of tape which are arranged vertically at intervals at the back of the waist and across the ribbed section of the garment and are detachably connected with the garment. These 40 tapes have the rubber threads which they contain arranged vertically so that when the ribbed band section is stretched, the tapes are also stretched and take a large 45 part of the strain and they act quickly to return the parts to their original condition or to such condition as to best serve the comfort of the wearer.

45 In the accompanying drawings:—

Figure 1 shows a front elevation of a bifurcated union suit or garment with my improvements applied.

Fig. 2 is a detail view on an enlarged 50 scale showing the elastic waist band section and the elastic tapes associated therewith.

Fig. 3 shows a section on the line 3—3 of Fig. 2.

The garment shown in Fig. 1 is in general 55 outline of well known construction and it is provided with a waist band section A at the rear made of elastic or semi-

elastic material in well known ways. The part A may be made of ribbed cloth, having considerable elasticity, in a vertical direction and also to some extent lengthwise or horizontally, and it is attached to the rear portion of the garment along its longitudinal and end edges in the usual way. The manner in which this is done is clearly 65 indicated in Fig. 3.

As indicated by dotted lines in Fig. 2, the section A can be stretched vertically to a considerable extent and when the garment is new good results are obtained, but 70 soon the stretchable cloth becomes permanently stretched and bags or sags and no longer accomplishes the purposes for which it is intended. To remedy these defects I employ a plurality of tapes B of elastic 75 webbing which are attached to the garment in the manner indicated in Fig. 3. They are arranged crosswise of the section A with the threads of rubber which they contain running vertically. A plurality of 80 tapes should be used. I have shown three as this number is ordinarily sufficient. When the garment is stretched, the section A is extended and at the same time the 85 tapes are lengthened and relieve the section A of much of the strain. As soon as the strain is removed, the tapes assist in returning the parts to normal condition.

My improvements may be easily applied to garments of well known construction 90 without material change therein.

As shown in Fig. 3 the edges of the cloth A are turned before they are attached to the body of the garment. It will be observed that the elastic tapes B are detachably secured to the part A. Any suitable 95 detachable fastening device may be employed; the drawings indicate snap fasteners of well known construction. In this way, the parts B may be removed from the 100 garment before the latter is washed.

I claim as my invention:

A union garment having a waist section of stretchable material across which extends at suitable intervals a plurality of 105 elastic tapes which relieve the section of strain and assists in returning the parts to normal condition said tapes being connected with the garment by detachable fastenings, for the purpose specified.

110 In testimony whereof I have hereunto subscribed my name.

THOMAS WESLEY HOOK.
